[57] CLAIM

The ornamental design for a shaving razor holder, as shown and described.

DESCRIPTION

FIG. 1 is a front elevation view of a shaving razor holder showing my new design;

FIG. 2 is a back elevation view of the invention thereof;

FIG. 3 is an end view thereof;

FIG. 4 is a bottom view thereof;

FIG. 5 is a top plan view thereof; and,

FIG. 6 is an opposite end view thereof showing the new design.

The broken line showing of the shaving razors in FIG. 1 and the mounting pad with adhesive layer in FIGS. 3 through 6 are for illustrative purposes only and form no part of the claimed design.
